ABSTRACT

Novel substituted-dibenzo[c,e]azepin-5-ones. The dibenzo[c,e]azepin-5-ones disclosed herein are potent anti-inflammatory, anti-pyretic and analgesic agents. Also included herein are pharmaceutical compositions containing said dibenzo[c,e]azepin-5-one compounds as an active ingredient, and methods of treating inflammation, fever and pain in patients by administering said compounds. Further encompassed is 6,7-dihydro-5H-dibenzo[c,e]azepin-5-one possessing novel anti-inflammatory, anti-pyretic and analgesic activities.

13 Claims, No Drawings

DIBENZO(C,E)AZEPIN-5-ONES

This invention relates to novel substituted-dibenzo [c,e]azepin-5-ones and methods for preparing the same. Also included within the scope of the invention are pharmaceutical compositions containing said dibenzo[c,e]-azepin-5-one compounds as active ingredients. The novel dibenzo[c,e]azepin-5-ones of the invention are potent anti-inflammatory, anti-pyretic and analgesic agents which are effective in the method of counteracting inflammation, pain and fever.

In the past, numerous compounds have been widely used in the treatment of inflammation, pain and fever. The compounds employed in said treatment have consisted of both steroids and non-steroids. These compounds have shown side effects ranging from a simple headache to psychic and gastrointestinal disturbances.

In a continuous search for potent anti-inflammatory, anti-pyretic and analgesic agents, we have found a class of novel dibenzo[c,e]azepin-5-ones which are highly effective in the treatment of inflammation, pain and fever. The novel dibenzo[c,e]azepin-5-ones are of value in the treatment of arthritic and dermatological disorders of like conditions responsive to anti-inflammatory drugs. In general they are indicated for a wide variety of conditions where one or more of the symptoms of inflammation, fever and pain are manifested. Included within this category are diseases such as rheumatoid arthritis, osteo-arthritis, gout, infectious arthritis and rheumatic fever. As indicated above the compounds utilized in the practice of the invention also possess a useful degree of analgesic and antipyretic activity.

Further encompassed within the scope of the invention is 6,7-dihydro-5H-dibenzo[c,e]azepin-5-one, a compound known to the art (U.S.S.R. Pat. No. 261,390 issued Jan. 13, 1970 and U.S. Pat. No. 3,551,414 issued Dec. 29, 1970) but having no disclosed pharmaceutical utility. This known compound has unexpectedly been found to possess potent anti-inflammatory, antipyretic and analgesic activities.

The novel 6,7-dihydro-5H-dibenzo[c,e]azepin-5-one compounds of the invention are represented by the general structure below:

wherein

R₁, R₂, R₉ and R₁₀ are each
hydrogen,
halogen, such as
fluorine,
bromine and the like,
alkoxy, such as
methoxy,
ethoxy,
isopropoxy,
butoxy and the like,
nitrile,
hydroxy.

nitro,
amino,
alkyl, such as
methyl
propyl,
ethyl,
t-butyl and the like,
dialkylamino, such as
dimethylamino,
diethylamino,
methylethylamino and the like,
dialkenylamino, such as
dibutenylamino,
dipentenylamino,
dipropenylamino and the like,
alkylamino, such as
methylamino,
ethylamino,
butylamino and the like,
arylarnino, such as
anilino,
o,m or p-tolylamino,
anisidino and the like,
aralkylamino, such as
benzylamino,
phenethylamino,
o,m or p-methoxybenzylamino,
o,m or p-halobenzylamino,
alkenylamino, such as
butenylamino,
propenylamino and the like,
aryol, such as
benzoyl,
o,m or p-halobenzoyl,
o,m or p-methylthiobenzoyl,
aryolamino, such as
benzoylamino,
o,m or p-halobenzoylamino,
o,m or p-methoxybenzoylamino,
o,m or p-methylthiobenzoylamino,
acylarnino, such as
acetylarnino,
propionylarnino,
butyrylarnino and the like,
acyl, such as
acetyl,
propionyl,
butyryl and the like,
mercapto,
alkylthio, such as
methylthio,
ethylthio,
butylthio and the like,
arylthio, such as
phenylthio,
o,m or p-tolylthio and the like,
aralkylthio, such as
benzylthio,
o,m or p-methylbenzylthio,
o,m or p-methoxybenzylthio,
phenethylthio and the like,
alkenylthio, such as
butenylthio,
propenylthio and the like,
alkylsulfoxide, such as
methylsulfoxide,
ethylsulfoxide,

propylsulfoxide and the like,
 alkenylsulfoxide, such as
 allylsulfoxide and the like,
 arylsulfoxide, such as
 phenylsulfoxide,
 o,m or p-tolylsulfoxide and the like,
 aralkylsulfoxide, such as
 benzylsulfoxide,
 phenethylsulfoxide and the like,
 alkylsulfone, such as
 methylsulfone,
 ethylsulfone,
 isopropylsulfone,
 butylsulfone and the like,
 alkenylsulfone, such as
 butenylsulfone,
 propenylsulfone and the like,
 arylsulfone, such as
 phenylsulfone,
 o,m or p-tolylsulfone and the like,
 aralkylsulfone, such as
 benzylsulfone,
 phenethylsulfone,
 o,m or p-methylbenzylsulfone and the like,
 carbamoyl,
 mono- or dialkylcarbamoyl, such as
 methylcarbamoyl,
 dimethylcarbamoyl,
 diethylcarbamoyl,
 butylcarbamoyl and the like,
 arylcarbamoyl, such as
 phenylcarbamoyl,
 anisidinocarbamoyl, and the like,
 aralkylcarbamoyl, such as
 benzylcarbamoyl,
 o,m or p-methylbenzylcarbamoyl
 phenethylcarbamoyl and the like,
 mono- or dialkenylcarbamoyl, such as
 propenylcarbamoyl,
 butenylcarbamoyl,
 pentenylcarbamoyl,
 dipropenylcarbamoyl and the like,
 amidino,
 ureido,
 carbamoyloxy
 N-alkylcarbamoyloxy, such as
 N-methylcarbamoyloxy
 N-ethylcarbamoyloxy
 N-isopropylcarbamoyloxy
 N-butylcarbamoyloxy and the like,
 N-dialkylcarbamoyloxy, such as
 N-dimethylcarbamoyloxy,
 N-diethylcarbamoyloxy
 N-dibutylcarbamoyloxy and the like,
 haloalkyl, such as
 difluoromethyl,
 fluoromethyl,
 trifluoromethyl,
 trichloromethyl,
 bromomethyl,
 chloromethyl,
 tribromoethyl and the like,
 sulfamyl,
 alkylsulfamyl, such as
 methylsulfamyl,
 ethylsulfamyl,
 isopropylsulfamyl,

butylsulfamyl and the like,
 dialkylsulfamyl, such as
 dimethylsulfamyl,
 diethylsulfamyl,
 methylethylsulfamyl,
 di-isopropylsulfamyl and the like,
 haloalkoxy, such as
 trifluoromethoxy,
 difluoromethoxy,
 dibromoethoxy,
 dichloromethoxy,
 trifluoroethoxy,
 fluoromethoxy and the like,
 haloalkylthio, such as
 trifluoromethylthio,
 difluoromethylthio,
 fluoromethylthio,
 bromomethylthio,
 dichloroethylthio,
 trifluoroethylthio and the like,
 alkenyloxy, such as
 propenyloxy,
 ethenyloxy and the like,
 aryloxy, such as
 phenoxy,
 o,m or p-halophenoxy,
 o,m or p-tolyloxy,
 o,m or p-methoxyphenoxy and the like,
 aralkyloxy, such as
 benzyloxy,
 phenethyloxy,
 o,m or p-methoxybenzyloxy,
 o,m or p-methylbenzyloxy and the like,
 carboxyalkyl, such as
 carboxymethyl,
 α -carboxyethyl and the like,
 carboxyalkenyl, such as
 α -carboxy(ethylidenyl),
 α -carboxy(butenyl) and the like;
 R₃ is hydrogen,
 alkyl, such as
 methyl,
 ethyl,
 propyl and the like,
 acyl, such as
 acetyl,
 propionyl,
 butyryl and the like,
 aroyl, such as
 o,m or p-halobenzoyl,
 benzoyl and the like,
 alkoxyalkyl, such as
 methoxymethyl,
 methoxyethyl,
 propyloxymethyl and the like,
 aminoalkyl, such as
 aminoethyl,
 aminopropyl,
 aminobutyl and the like,
 carboxyalkyl, such as
 carboxymethyl,
 carboxyethyl,
 carboxypropyl,
 carboxybutyl and the like,
 hydroxyalkyl, such as
 hydroxymethyl,
 hydroxyethyl,

hydroxybutyl and the like, alkenyl, such as propenyl, butenyl and the like; and alkoxy carbonyl, such as methoxycarbonyl, ethoxycarbonyl, isopropoxy carbonyl and the like, carbamoyl, carboxyalkoxy, such as carboxymethoxy, carboxyethoxy, carboxyisopropoxy and the like, mercaptalkyl, such as mercaptomethyl, mercaptoethyl, mercaptoisopropyl, mercaptobutyl and the like, alkylthioalkyl, such as methylthiomethyl, methylthiomethyl, methylthioethyl, ethylthiomethyl, ethylthioethyl, isopropylthioethyl and the like, aralkylthioalkyl, such as benzylthioethyl, o,m or p-methylbenzylthioethyl, o,m or p-methoxybenzylthiomethyl, phenethylthioethyl, benzylthiomethyl and the like, aralkylsulfinylalkyl, such as benzylsulfinylethyl, phenethylsulfinylethyl, o,m or p-methylbenzylsulfinylmethyl, o,m or p-methoxybenzylsulfinylethyl, o,m or p-halobenzylsulfinylethyl, o,m or p-aminobenzylthioethyl and the like; R₄ is hydrogen, acylimido, or acetyl imido; with the proviso that when R₃ is hydrogen or alkyl at least one of R₁, R₂ and R₄ is other than hydrogen.

This invention may be better understood from the details shown below.

The novel compounds of the invention are prepared by employing 6,7-dihydro-5H-dibenzo[c,e]azepin-5-one (A) as the starting material wherein R₄ is hydrogen. To obtain the compounds of the invention wherein R₃ is hydrogen, said starting material (A) is treated with a nitrating reagent whereby there is obtained a mono-nitro derivative in the ring containing position 8,9,10 and 11 (B) or a dinitro derivative where the other ring containing position 1,2,3 and 4 is nitrated (L). The nitro substituent of the compound thus obtained is reduced to obtain mono- or di-amino-6,7-dihydro-5H-dibenzo[c,e]azepin-5-one (C). This amino compound is then diazotized and converted to the corresponding mono- or di-haloazepin-5-one (D). Treating the compound thus obtained with a cyano forming reagent yields the corresponding mono- or di-cyanoazepin-5-one (E). This compound is then hydrolyzed to obtain the corresponding mono- or di-carbamoylazepin-5-one (F). Said carbamoyl compound is further hydrolyzed to obtain the corresponding acid (G). This compound is then treated with a trihalo forming reagent to yield the corresponding mono- or di-trihalomethyl compound (V). Said mono- or di-trihalo compound (V) is then treated with an R₃ forming re-

gent thereby obtaining the corresponding N-substituted compound (W). The carboxy compound (G) is then treated with an acid halide forming reagent to obtain the corresponding mono- or di-acid halide (H). Reacting this compound with an amino reagent gives the corresponding mono- or di-substituted-carbamoyl (I). Said Mono- or di-substituted carbamoyl compound (I) is then treated with an R₃ forming reagent whereby there is obtained the corresponding N-substituted compound 10 (J). Also, compound (E) is treated with an alkoxyamidino forming reagent to obtain the corresponding mono- or di-(alkoxyamidino)azepin-5-one (Q'). Said mono- or di-(alkoxyamidino) compound (Q') is then converted to the corresponding mono- or di-(amidino)-15 6,7-dihydro-azepin-5-one (R').

The novel mono- or di-substituted-6,7-dihydro-N-substituted-5H-dibenzo[c,e]azepin-5-ones are obtained as shown below. 6,7-Dihydro-5H-dibenzo[c,e]azepin-5-one (A) is treated with an R₃ forming reagent whereby there is obtained N-R₃-6,7-dihydro-5H-dibenzo[c,e]azepin-5-one (R). Mono- or di-nitro-6,7-dihydro-5H-dibenzo[c,e]azepin-5-one (B) is treated with an R₃ reagent to obtain mono- or dinitro-N-R₃-6,7-dihydro-5H-dibenzo[c,e]azepin-5-one (S). Compound 20 (S) is then reduced to obtain the corresponding mono- or di-amino-6,7-dihydro-5H-dibenzo[c,e]azepin-5-one (Y). The compound (Y) thus obtained is then treated with a diazotizing reagent in the presence of an acid to obtain the corresponding mono- or di-hydroxy-dibenzo[c,e]azepin-5-one (B'). Treating said mono- di-hydroxy compound (B') with an alkyl halide or aralkyl halide yields the corresponding mono- or di-(alkoxy or aralkoxy)-6,7-dihydro-dibenzo[c,e]azepin-5-one (A'). Compound (A') is then nitrated to obtain the corresponding nitro-, mono- or di-(alkoxy or aralkoxy)-azepin-5-one (J'). Compound (B') is treated with an alkylcarbamoyloxy forming reagent whereby there is obtained the corresponding mono- or di-alkyl-carbamoyloxy-azepin-5-one (L'). Also, said compound 25 (B') can be treated with a haloalkoxy forming reagent to obtain the corresponding mono- or di-(haloalkoxy)-azepin-5-one (K'). Treating compound (Y), N-substituted-mono- or di-amino-6,7-dihydro-5H-dibenzo[c,e]azepin-5-one with a mercapto forming reagent gives the corresponding mono- or di-mercapto-azepin-5-one (M'). Said mono- or di-mercapto compound (M') is then converted to the corresponding mono- or di-(haloethylthio)-azepin-5-one (O'). Also, compound (Y) is treated with a ureido forming reagent to obtain the corresponding mono- or di-(ureido)-6,7-dihydro-azepin-5-one (N').

Compound (C), mono- or di-amino-6,7-dihydrodibenzo[c,e]azepin-5-one, is treated with an acyl, aroyl or aralkyloyl forming reagent whereby there is obtained the corresponding mono- or di-acetyl, aroyl or aralkyloyl-6-acetyl, aroyl or aralkyloyl-azepin-5-one (T). Said compound (T) is then nitrated to obtain the corresponding nitro-mono- or di-(acetyl amino, aroyl amino or aralkoyl amino)-6,7-dihydro-azepin-5-one (P'). Also, compound (C) is treated with a diazotizing reagent in the presence of an acid to obtain mono- or di-hydroxy- 6,7-dihydro-dibenzo[c,e]azepin-5-one (M).

The novel mono- or di-sulfur derivatives of the invention are obtained by employing compound (D), mono- or di-halo-6,7-dihydro-dibenzo[c,e]azepin-5-one as the starting material. Compound (D) is treated with an R₃

forming substituent to obtain the corresponding mono- or di-halo-N-substituted-azepin-5-one (N). Compound (N) is treated with an alkyl, aryl or alkyl-sulfide forming reagent to yield the corresponding mono- or di-alkyl, aryl or aralkylthio-azepin-5-one (U). If desired, the mono- or di-alkyl, aryl or aralkylthio substituent may be converted to the mercapto substituent. The compound (U) thus obtained is then treated with an oxidizing reagent to yield the corresponding mono- or di-alkyl, aryl or aralkyl-sulfinyl-azepin-5-one (X). Further oxidation of this sulfinyl compound gives the corresponding mono- or di-alkyl, aryl or aralkylsulfone-azepin-5-one (C').

To obtain the novel compounds of the invention wherein R_4 is other than hydrogen, 6,7-dihydro-5H-dibenzo[c,e]azepin-5-one (A) or mono- or di-nitro-N-substituted-6,7-dihydro-dibenzo[c,e]azepin-5-one (S) is employed as the starting material. Said starting material (A or S) is treated with an N-halo-imide to yield the corresponding 7-imido-azepin-5-one compound (K or Z).

To obtain the novel mono- or di-(cyano, carbamoyl or carboxy)-N- R_3 -6,7-dihydro-dibenzo[c,e]azepin-5-one compounds of the invention wherein R_3 is as previously defined, mono- or di-cyano-6,7-dihydro-dibenzo[c,e]azepin-5-one (E) is employed as the starting material. Said starting material (E) is treated with an R_3 forming substituent whereby there is obtained mono- or di-cyano-N- R_3 -6,7-dihydro-dibenzo[c,e]azepin-

5-one (O). This compound is then hydrolyzed to obtain the corresponding mono- or dicarbamoyl-azepin-5-one (P). Said carbamoyl compound (P) is further hydrolyzed to yield the corresponding mono- or di-carboxy-azepin-5-one (Q).

Compound (A), 6,7-dihydro-5H-dibenzo[c,e]azepin-5-one, is treated with an alkoxy carbonyl forming reagent whereby there is obtained the corresponding 6-alkoxy carbonyl-azepin-5-one (E'). This compound is 10 then converted to the corresponding 6-aminocarbonyl-azepin-5-one (D'). Also, compound (A) is treated with an alkylthio alkyl forming reagent to obtain 6-(methylthiomethyl)-6,7-dihydro-5H-dibenzo[c,e]azepin-5-one (F'). The compound thus obtained is then 15 oxidized to yield the corresponding 6-(methylsulfinylmethyl)-6,7-dihydro-azepin-5-one (G').

The novel mono- or di-sulfamyl derivatives of the invention are obtained by employing compound (R) as 20 the starting material, wherein R_3 is as previously defined. Said starting material (R), N-substituted-6,7-dihydro-5H-dibenzo[c,e]azepin-5-one is treated with a sulfamyl forming reagent whereby there can be obtained the corresponding N-substituted-mono- or di-sulfonyl halide-azepin-5-one (H) intermediate, and the corresponding N-substituted-mono- or di-sulfamyl-azepin-5-one (I').

Flow Sheet I represents the general sequence for the preparation of the novel compounds of the invention.

wherein R₁, R₂, R₃, R₄, R₉ and R₁₀ are as previously defined and R₅ is alkyl such as methyl, ethyl, propyl and the like; phenyl; aralkyl such as benzyl, phenethyl, o, m or p-methylbenzyl and the like; and R₆, R₇ and R₈ are each alkyl such as methyl, ethyl, propyl and the like; aryl such as phenyl, o, m or p-methylphenyl and the like; and aralkyl such as benzyl, phenethyl, o, m or p-methylbenzyl, o, m or p-methoxybenzyl and the like; R₁₁ is alkyl such as methyl, ethyl, isopropyl and the like; Y is halogen such as fluorine, bromine and the like; X is an integer ranging from 1 - 4; and N is an integer equal to 0 to 1.

REACTIONS AND CONDITIONS

60 Step 1.1

Step 11. The reaction is performed in an acid, such as nitric acid or the combination of an acid such as nitric-sulfuric, nitric-acetic, and the like, or an acid in the presence of a nitrating reagent such as alkali nitrates (sodium, potassium, etc.), at temperatures ranging from 0°C. to 60°C. Of particular preference is the combination of sulfuric acid and potassium nitrate at room temperature until the reaction is complete.

Step 1.2

The reaction is performed by hydrogenation over a catalyst such as palladium-on-carbon, platinum, Raney nickel, and the like, in the presence of an inert solvent such as ethanol, propanol, butanol, benzene, toluene, tetrahydrofuran, ether and the like, at temperatures ranging from 0°C. to near reflux. Of particular preference is the combination of palladium-on-carbon and ethanol at room temperature until the reaction is complete.

Step 1.3

The reaction is performed in a water-acid solvent such as water-sulfuric acid, water-fluoroboric acid, water-hydrochloric acid, water-p-toluenesulfonic acid and the like, in the presence of a diazotizing agent such as sodium nitrite, nitrous acid and the like, with a halogenating reagent such as cuprous halide (cuprous chloride, cuprous bromide, cuprous fluoride and the like), at temperatures ranging from 0°C. to reflux. Of particular preference is the combination of water-fluoroboric acid and sodium nitrite at 90°C. until the reaction is complete.

Step 1.4

The reaction is performed in an inert solvent such as dimethyl formamide, benzene, toluene, ethanol, dimethylsulfoxide, dimethoxyethane, and the like, with a cyano forming reagent such as cuprous cyanide, alkali cyanide (potassium, lithium and the like), at temperatures ranging from room temperature to reflux. Of particular preference is the combination of dimethylformamide and cuprous cyanide at reflux until the reaction is complete.

Step 1.5

The reaction is performed in an acid such as sulfuric, phosphoric, methanesulfonic and the like, at temperatures ranging from 0°C. to 50°C. Of particular preference is sulfuric acid at room temperature until the reaction is complete.

Step 1.6

The reaction is performed in an inert solvent such as chloroform, benzene, toluene, dimethylsulfoxide, ether and the like, with a N-halo-acylimide such as N-bromosuccinimide, N-chlorosuccinimide, and the like, at temperatures ranging from near reflux to reflux. Of particular preference is the combination of chloroform and N-bromosuccinimide at reflux until the reaction is complete.

Step 1.7

The reaction is performed in an inert solvent such as ether, dimethylsulfoxide, tetrahydrofuran, benzene, toluene and the like, in the presence of a base such as sodium hydride, sodium amide, potassium hydroxide and the like with an alkyl halide such as methyl iodide, propyl bromide, butyl iodide and the like, or an alkenyl halide such as allyl bromide, vinyl iodide, propenyl chloride and the like, at temperatures ranging from 0°C. to 60°C. Of particular preference is the combination of dimethylformamide, sodium hydride and allyl bromide at room temperature until the reaction is complete.

Steps 1.9 and 1.13

The reaction is performed with an acyl, aroyl or aralkoyl forming reagent such as acetic anhydride, propionic anhydride, benzoic anhydride, benzoyl chloride, phenyl propionyl chloride and the like, at temperatures ranging from 60°C. to near reflux. Of particular preference is acetic anhydride at 90°C.-95°C. until the reaction is complete.

Step 1.11

The reaction is performed by diazotizing the amine in an aqueous acid solution such as sulfuric acid, hydrochloric acid, and the like, with sodium nitrite, and raising the temperature from 0°C. to 100°C. until the reaction is complete.

Step 1.12

The reaction is performed in an inert solvent such as dimethylformamide, benzene, tetrahydrofuran, ether, toluene, and the like, in the presence of a base such as

10 sodium methoxide, ammonium hydroxide, potassium hydroxide and the like, with alkyl halide, aryl halide or aralkyl halide such as methyl iodide, propyl iodide, benzyl iodide and phenethyl chloride at temperatures ranging from 0°C. to 50°C. Of particular preference is the combination of dimethylformamide, sodium methoxide and methyl iodide at room temperature until the reaction is complete.

Step 1.14

20 The reaction is performed with copper, lutidine and dialkyldisulfide such as dimethyldisulfide, diethyldisulfide, diphenyldisulfide, benzylidisulfide and the like-complex at temperatures ranging from 75°C. to 175°C. Of particular preference is dimethyldisulfide complex at 155°C. until the reaction is complete.

Step 1.15

25 The reaction is performed in a combination of inert solvents such as acetone-methanol, water-acetone, methanol-water, benzene-ethanol and the like, with an oxidizing agent such as sodium periodate, oxygen, hydrogen peroxide and the like, at temperatures ranging from 20°C. to 50°C. Of particular preference is the combination of acetone-methanol and sodium periodate at room temperature until the reaction is complete.

Step 1.16

30 The reaction is performed in an acid such as acetic acid, propionic acid, N-butyric acid and the like, with an oxidizing agent such as hydrogen peroxide, sodium periodate, oxygen and the like, in the presence of the acid employed as the solvent, at temperatures ranging from 0°C. to 60°C. Of particular preference is the combination of acetic acid and hydrogen peroxide-acetic acid at room temperature until the reaction is complete.

Step 1.17

35 The reaction is performed with an acid such as sulfuric acid, hydrochloric acid, p-toluenesulfonic acid, methanesulfonic acid and the like, in the presence of a diazotizing reagent such as sodium nitrite, nitrous acid and the like, at temperatures ranging from 40°C. to 100°C. Of particular preference is the combination of sulfuric acid and sodium nitrite at 75°C. until the reaction is complete.

Step 1.18

40 The reaction is performed with or without an inert solvent such as ether, benzene, and the like, and an acid halide forming reagent such as phosphorus trichloride, phosphorus pentachloride, thionyl chloride, phosphorus tribromide and the like, at temperatures ranging from room temperature to reflux. Of particular preference is thionyl chloride at reflux until the reaction is complete.

Step 1.19

45 The reaction is performed with an aqueous mono- or di-alkylamine such as methylamine, dimethylamine, propylamine; mono- or di-arylamine or mono- or di-aralkylamine such as aniline, diphenylamine, benzylamine, dibenzylamine, β -phenethylamine and the like,

at temperatures ranging from 10°C. to 60°C. Of particular preference is dimethylamine at room temperature until the reaction is complete.

Step 1.20

The reaction is performed in the presence of a hydrohalic acid such as hydrochloric acid, hydrobromic acid, hydrofluoric acid and the like, with a halogenating reagent such as sulfur tetrafluoride, sulfur tetrachloride, sulfur tetrabromide and the like, in a stainless steel container at temperatures ranging from 50°C. to 175°C. Of particular preference is the combination of hydrofluoric acid and sulfur tetrafluoride at 120°C. until the reaction is complete.

Step 1.21

The reaction is performed in an inert solvent such as dimethylformamide, tetrahydrofuran, dioxane and the like, with an alkyl halocarbonate such as ethyl chlorocarbonate, methyl chlorocarbonate and the like, at temperatures ranging from 0°C. to room temperature. Of particular preference is the combination of dimethylformamide and ethyl chlorocarbonate at 10°C. until the reaction is complete.

Step 1.22

The reaction is performed in a base such as ammonium hydroxide, methylamine, methylethylamine, dimethylamine, and the like, at temperatures ranging from 10°C. to 50°C. Of particular preference is ammonium hydroxide at 35°C. until the reaction is complete.

Step 1.23

The reaction is performed in an inert solvent such as dimethylformamide, tetrahydrofuran, dioxane, benzene and the like, in the presence of a base such as NaH, LiH and the like, with a haloalkyl alkyl sulfide such as chloromethyl methyl sulfide, chloroethyl ethyl sulfide and the like, at temperatures ranging from 0°C. to room temperature. Of particular preference is the combination of dimethylformamide and chloromethyl methyl sulfide at 10°C. until the reaction is complete.

Step 1.24

The reaction is performed in a solvent such as acetone, acetic acid, dimethylformamide and the like, with an oxidizing agent such as sodium periodate, potassium periodate and the like at temperatures ranging from 10°C. to 40°C. Of particular preference is the combination of sodium periodate and acetone at room temperature until the reaction is complete.

Steps 1.25 and 1.26

The reaction is performed in a halosulfonic acid such as chlorosulfonic acid. This intermediate is added to a base such as ammonium hydroxide, methylamine, dimethylamine and the like, at temperatures below 30°C. until the reaction is complete.

Steps 1.27 and 1.31

The reaction is performed in an inert solvent such as dimethylformamide, tetrahydrofuran, dioxane and the like, with a haloalkene at temperatures ranging from 60°C. to 120°C. in a sealed container. Of particular preference is the combination of dimethylformamide and fluoro-chloro ethylene at 100°C. until the reaction is complete.

Step 1.28

The reaction is performed in an inert solvent such as tetrahydrofuran, methylene chloride, dioxane, dimethylformamide and the like, with an alkyl isocyanate such as ethyl isocyanate, methyl isocyanate and the like, at temperatures ranging from 10°C. to 50°C. Of particular

preference is the combination of dioxane and ethyl isocyanate at room temperature until the reaction is complete.

Step 1.29

5 The reaction is performed in an acid such as acetic, propionic, hydrochloric and the like, with an alkali isocyanate such as potassium isocyanate, sodium isocyanate and the like at temperatures ranging between 10°C. and 40°C. Of particular preference is the combination of acetic acid and potassium isocyanate at room temperature until the reaction is complete.

Step 1.30

The reaction is performed with a diazotizing agent, treated with an alkali alkyl xanthate such as potassium xanthate, sodium xanthate and the like, and hydrolyzed.

Step 1.32 and 1.33

15 The reaction is performed in an alkanol solvent such as methanol, ethanol, propanol and the like and a reagent such as hydrochloride, hydrobromide and the like. This intermediate is added to a base such as ammonia, methylamine, dimethylamine and the like, at temperatures ranging between 0°C. and room temperature. Of particular preference is the combination of ethanol, hydrochloride and ammonia at 0°C. until the reaction is complete.

20 Representative compounds of the invention are:

9-fluoro-6,7-dihydro-5H-dibenzo[c,e]azepin-5-one
3,9-difluoro-6,7-dihydro-5H-dibenzo[c,e]azepin-

5-one
3,9-dinitro-6,7-dihydro-5H-dibenzo[c,e]azepin-

5-one
6,7-dihydro-5H-dibenzo[c,e]azepin-5-one
6-acetyl-6,7-dihydro-5H-dibenzo[c,e]azepin-5-one

35 9-chloro-6,7-dihydro-5H-dibenzo[c,e]azepin-5-one
6-butyryl-6,7-dihydro-5H-dibenzo[c,e]azepin-5-one
9-nitro-6,7-dihydro-5H-dibenzo[c,e]azepin-5-one
6-allyl-6,7-dihydro-5H-dibenzo[c,e]azepin-5-one

9-amino-6,7-dihydro-5H-dibenzo[c,e]azepin-5-one
40 9-hydroxy-6,7-dihydro-5H-dibenzo[c,e]azepin-

5-one
6-hydroxymethyl-9-dimethylamino-6,7-dihydro-5H-
dibenzo[c,e]azepin-5-one

45 9-cyano-6,7-dihydro-5H-dibenzo[c,e]azepin-5-one
9-methoxy-6,7-dihydro-5H-dibenzo[c,e]azepin-

5-one
9-carbamoyl-6,7-dihydro-5H-dibenzo[c,e]azepin-

5-one
50 9-trifluoromethyl-6,7-dihydro-5H-dibenzo[c,e]aze-

pin-5-one
9-N,N'-dimethylcarbamoyl-6,7-dihydro-5H-diben-

zo[c,e]azepin-5-one
9-carboxy-6,7-dihydro-5H-dibenzo[c,e]azepin-5-one

55 9-methylmercapto-6,7-dihydro-5H-dibenzo[c,e]aze-

pin-5-one
6-methyl-6,7-dihydro-5H-dibenzo[c,e]azepin-5-one
6-acetyl-9-acetylamino-6,7-dihydro-5H-dibenzo[c-

60 ,e]azepin-5-one
6-methyl-9-nitro,6,7-dihydro-5H-dibenzo[c,e]aze-

pin-5-one
6-allyl-9-trifluoromethyl-6,7-dihydro-5H-dibenzo[c-

,e]-azepin-5-one
6-propionyl-3,9-di(dimethylamino)-6,7-dihydro-5H-
dibenzo[c,e]azepin-5-one

65 6-propionyl-9-fluoro-6,7-dihydro-5H-dibenzo[c,e]aze-

pin-5-one
3-fluoro-6,7-dihydro-5H-dibenzo[c,e]azepin-5-one

- 6-acetyl-3,9-dichloro-6,7-dihydro-5H-dibenzo[c,e]azepin-5-one
 3,9-difluoro-6-acetyl-6,7-dihydro-5H-dibenzo[c,e]azepin-5-one
 6-acetyl-3,9-diacetylamino-6,7-dihydro-5H-dibenzo[c,e]azepin-5-one
 6-butyryl-9-fluoro-6,7-dihydro-5H-dibenzo[c,e]azepin-5-one
 6-hydroxymethyl-9-cyano-6,7-dihydro-5H-dibenzo[c,e]azepin-5-one
 7-succinimido-6,7-dihydro-5H-dibenzo[c,e]azepin-5-one
 6-butyryl-9-hydroxy-6,7-dihydro-5H-dibenzo[c,e]azepin-5-one
 6-benzoyl-3,9-dinitro-6,7-dihydro-5H-dibenzo[c,e]azepin-5-one
 6-allyl-3,9-dinitro-6,7-dihydro-5H-dibenzo[c,e]azepin-5-one

The compounds of this invention are administered orally, topically, intravenously, or intramuscularly in the treatment of inflammation, fever and pain. Of particular preference is the oral form ranging from 10 to 2,000 mg./kg. of body weight per day. Of preference is 50-500 mg./kg. of body weight per day for varying periods of treatment as required. Comparable amounts of the compounds may be administered in topical or parenteral forms.

For these purposes the compounds of the invention may be administered orally, topically and parenterally in dosage unit formulations containing conventional non-toxic pharmaceutically acceptable carriers, adjuvants and vehicles. The term "parenteral" as used herein includes intravenous or intramuscular. In addition to the treatment of warm-blooded animals such as mice, rats, horses, dogs, cats, etc., the compounds of the invention are effective in the treatment of humans.

The pharmaceutical compositions containing the active ingredient may be in a form suitable for oral use, for example, as tablets, troches, lozenges, aqueous or oil suspensions, dispersible powders or granules, emulsions, hard or soft capsules, syrups or elixirs. Compositions intended for oral use may be prepared according to any method known to the art for the manufacture of pharmaceutical compositions and such compositions may contain one or more agents selected from the group consisting of sweetening agents, flavoring agents, coloring agents and preserving agents in order to provide a pharmaceutically elegant and palatable preparation. Tablets contain the active ingredient in admixture with non-toxic pharmaceutically acceptable excipients which are suitable for manufacture of tablets. These excipients may be, for example, inert diluents such as calcium carbonate, sodium carbonate, lactose, calcium phosphate or sodium phosphate; granulating and disintegrating agents, for example, maize starch or alginic acid; binding agents, for example, starch, gelatin or acacia; and lubricating agents, for example, magnesium stearate, stearic acid or talc. The tablets may be uncoated or they may be coated by known techniques to delay disintegration and absorption in the gastro-intestinal tract and thereby provide a sustained action over a longer period. For example, a time delay material such as glyceryl monostearate or glyceryl distearate alone or with a wax may be employed.

Formulations for oral use may also be presented as hard gelatin capsules wherein the active ingredient is

mixed with an inert solid diluent, for example, calcium carbonate, calcium phosphate or kaolin, or as soft gelatin capsules wherein the active ingredient is mixed with water or an oil medium, for example arachis oil, peanut oil, liquid paraffin or olive oil.

Aqueous suspensions contain the active materials in admixture with excipients suitable for the manufacture of aqueous suspensions. Such excipients are suspending agents, for example, sodium carboxymethylcellulose, 10 methyl-cellulose, hydroxypropylmethylcellulose, sodium alginate, polyvinylpyrrolidone, gum tragacanth and gum acacia; dispersing or wetting agents may be a naturally-occurring phosphatide, for example, lecithin, or condensation products of an alkylene oxide with fatty acids, for example, polyoxyethylene stearate, or condensation products of ethylene oxide with long chain aliphatic alcohols, for example, heptadecaethyleneoxycetanol, or condensation products of ethylene oxide with partial esters derived from fatty acids and a hexitol such as polyoxyethylene sorbitol monooleate, or condensation products of ethylene oxide with partial esters derived from fatty acids and hexitol anhydrides, for example, polyoxyethylene sorbitan monooleate. The said aqueous suspensions may also contain one or more preservatives, for example, ethyl or n-propyl p-hydroxy benzoate, one or more coloring agents, one or more flavoring agents and one or more sweetening agents, such as sucrose or saccharin.

Oily suspensions may be formulated by suspending the active ingredient in a vegetable oil, for example, arachis oil, olive oil, sesame oil, or coconut oil, or in a mineral oil such as liquid paraffin. The oil suspensions may contain a thickening agent, for example, beeswax, hard paraffin or cetyl alcohol. Sweetening agents, such as those set forth above, and flavoring agents may be added to provide a palatable oral preparation. These compositions may be preserved by the addition of an anti-oxidant such as ascorbic acid.

Dispersible powders and granules suitable for preparation of an aqueous suspension by the addition of water provide the active ingredient in admixture with a dispersing or wetting agent, suspending agent and one or more preservatives. Suitable dispersing or wetting agents and suspending agents are exemplified by those already mentioned above. Additional excipients, for example, sweetening, flavoring and coloring agents, may also be present.

The pharmaceutical compositions of the invention 50 may also be in the form of oil-in-water emulsions. The oily phase may be a vegetable oil, for example, olive oil or arachis oil, or a mineral oil, for example, liquid paraffin or mixtures of these. Suitable emulsifying agents may be naturally-occurring gums, for example, gum acacia or gum tragacanth, naturally-occurring phosphatides, for example, soya bean, lecithin, and esters or partial esters derived from fatty acids and hexitol anhydrides, for example, sorbitan mono-oleate, and condensation products of said partial esters with ethylene oxide, for example, polyoxyethylene sorbitan mono-oleate. The emulsions may also contain sweetening and flavoring agents.

Syrups and elixirs may be formulated with sweetening agents, for example, glycerol, sorbitol or sucrose. Such formulations may also contain a demulcent, a preservative and flavoring and coloring agents.

For intravenous and intramuscular administrations, the pharmaceutical compositions may be in the form of a sterile injectable preparation, for example, as a sterile

injectable aqueous or oleagenous suspension. This suspension may be formulated according to the known art using those suitable dispersing or wetting agents and suspending agents which have been mentioned above. The sterile injectable preparation may also be a sterile injectable solution or suspension in a non-toxic parenterally-acceptable diluent or solvent, for example, as a solution in a 1,3-butane diol. Among the acceptable vehicles and solvents that may be employed are water, Ringer's solution, and isotonic sodium chloride solution. In addition, sterile, fixed oils are conventionally employed as a solvent or suspending medium. For this purpose, any bland fixed oil may be employed including synthetic mono- or di-glycerides. In addition, fatty acids such as oleic acid find use in the preparation of injectables.

The amount of active ingredient that may be combined with the carrier materials to produce a single dosage form will vary depending upon the host treated and the particular mode of administration. For example, a formulation intended for the oral administration of humans may contain from 5 mg. to 10 grams of active agent compounded with an appropriate and convenient amount of carrier material which may vary from about 5 to about 95 percent of the total composition. Dosage unit forms will generally contain between from about 175 mg. to about 1.75 g. of active ingredient. Comparable amounts of the compounds may be administered in topical or parenteral forms.

It will be understood, however, that the specific dose level for any particular patient will depend upon a variety of factors including the activity of the specific compound employed, the age, body weight, general health, sex, diet, time of administration, route of administration, rate of excretion, drug combination and the severity of the particular disease undergoing therapy.

The starting material employed in the invention is represented by compound (A) which is shown in Flow Sheet I. Said starting material is known and processes for its preparation can be found in the literature. For example, see U.S.S.R. Patent 261,390 and U.S. Pat. No. 3,551,414.

The following examples illustrate the preparation of the various 6,7-dibenzo[c,e]azepin-5-one compounds described herein as anti-inflammatory, anti-pyretic and analgesic agents. The examples should be construed as illustrations of the invention rather than limitations thereof.

EXAMPLE 1

9-Nitro-6,7-dihydro-5H-dibenzo[c,e]azepin-5-one

A solution of 4.2 g. (.02 mole) of 6,7-dihydro-5H-dibenzo[c,e]azepin-5-one in 60 ml. of concentrated sulfuric acid is cooled to 0°C. and to it is added, with stirring, a solution containing 2 g. of potassium nitrate in 20 ml. of sulfuric acid over a period of 1 hour at a temperature below 5°C. The reaction is then stirred for 5 hours at room temperature, poured onto ice, filtered and washed with water and sodium bicarbonate solutions. The crude product, 9-nitro-6,7-dihydro-5H-dibenzo[c,e]azepin-5-one, is recrystallized from dimethylformamide, m.p. 250-252°C.

EXAMPLE 2

9-Amino-6,7-Dihydro-5H-dibenzo[c,e]azepin-5-one

Five grams of 9-nitro-6,7-dihydro-5H-dibenzo-[c,e]-azepin-5-one in 150 ml. of ethanol is hydrogenated in the presence of 1 g. of 5% palladium-on-charcoal. The

catalyst is removed by filtration, the solvent concentrated in vacuo and the residue is extracted with dilute hydrochloric acid. The acid extracts are neutralized with ammonium hydroxide to yield the crude product,

5 9-amino-6,7-dihydro-5H-dibenzo[c,e]azepin-5-one. This product is recrystallized from dimethylformamide by the addition of ether, m.p. 275-279°C.

When 9-nitro-6-acetyl, benzoyl, or methyl-6,7-dihydro-5H-dibenzo[c,e]azepin-5-one is substituted

10 for 9-nitro-6,7-dihydro-5H-dibenzo[c,e]azepin-5-one, there is obtained 9-amino-6-acetyl, benzoyl, or methyl-6,7-dihydro-5H-dibenzo[c,e]azepin-5-one.

EXAMPLE 3

15 9-Fluoro-6,7-dihydro-5H-dibenzo[c,e]azepin-5-one

To 1.1 g. (.005 mole) of 9-amino-6,7-dihydro-5H-dibenzo[c,e]azepin-5-one in 3.5 ml. of 48% fluoboric acid at 0°C. is added a solution containing 415 mg. of sodium nitrite and 2 ml. of water over 10 minutes. The

20 reaction mixture is maintained at 0°C. for 20 minutes, then cooled with dry ice-acetone to precipitate a solid. The solid is suspended in 75 ml. of heptane and heated on the steam-bath for 3 hours at 90°C., cooled and decanted from a tacky solid which is extracted with 30 ml.

25 of warm methylene chloride. The extract is diluted with petroleum ether to crystallize the boron trifluoride complex of the 9-fluoro product. This is decomposed by dissolving in ethanol and adding 2.5 N sodium hydroxide until the product, 9-fluoro-6,7-dihydro-5H-dibenzo[c,e]azepin-5-one, precipitates, m.p. 205-206°C.

When 6-acetyl, benzoyl, methyl or allyl-9-amino-6,7-dihydro-5H-dibenzo[c,e]azepin-5-one is substituted for

30 9-amino-6,7-dihydro-5H-dibenzo[c,e]azepin-5-one, there is obtained 6-acetyl, benzoyl, methyl or allyl-9-fluoro-6,7-dihydro-5H-dibenzo[c,e]azepin-5-one.

EXAMPLE 4

40 6-Acetyl-9-fluoro-6,7-dihydro-5H-dibenzo[c,e]azepin-5-one

To 2 g. of 9-fluoro-6,7-dihydro-5H-dibenzo[c,e]azepin-5-one is added 20 ml. of acetic anhydride. The resulting mixture is heated on the steam-bath at 90-95°C.

45 overnight. The excess solvent is removed in vacuo and the residue crystallizes upon addition of ether. The crude product, 6-acetyl-9-fluoro-6,7-dihydro-5H-dibenzo-[c,e]-azepin-5-one is crystallized from benzene.

EXAMPLE 5

9-Cyano-6,7-dihydro-5H-dibenzo[c,e]azepin-5-one

A mixture which contains 5 g. (.022 mole) of 9-bromo-6,7-dihydro-5H-dibenzo[c,e]azepin-5-one and 4.5 g. of cuprous cyanide is stirred and refluxed in 150 ml. of dry dimethylformamide. After 20 hours, the reaction mixture is concentrated to about half the original volume, cooled and added to 100 ml. of ferric chloride solution (4 parts ferric chloride, 1 part concentrated hydrochloric acid and 6 parts water). The reaction is then stirred for 30 minutes and diluted with 100 ml. of water. The mixture is extracted with 3 x 250 ml. of ethyl acetate. The compound extracts are

60 washed with water and then with aqueous sodium bicarbonate. The ethyl acetate is evaporated and the residue is purified by crystallization from dimethylformamide-ether to obtain the product, 9-cyano-6,7-dihydro-5H-dibenzo[c,e]azepin-5-one, m.p. 272-274°C.

When 6-methyl or allyl-9-fluoro-6,7-dihydro-5H-dibenzo[c,e]azepin-5-one is substituted for 9-bromo-6,7-dihydro-5H-dibenzo[c,e]azepin-5-one, there is obtained 6-methyl or allyl-9-cyano-6,7-dihydro-5H-dibenzo[c,e]azepin-5-one.

EXAMPLE 6

9-Carbamyl-6,7-dihydro-5H-dibenzo[c,e]azepin-5-one

Six hundred Mg. (.002 mole) of 9-cyano-6,7-dihydro-5H-dibenzo[c,e]azepin-5-one is dissolved in 15 ml. of concentrated sulfuric acid and allowed to stand at room temperature overnight. The solution is then poured onto ice and the crude product, 9-carbamyl-6,7-dihydro-5H-dibenzo[c,e]azepin-5-one, is filtered. The crude product is recrystallized from dimethylformamide-water, m.p. 298°C.

When 6-acetyl, benzoyl, methyl or allyl-9-cyano-6,7-dihydro-5H-dibenzo[c,e]azepin-5-one is substituted for 9-cyano-6,7-dihydro-5H-dibenzo[c,e]azepin-5-one, there is obtained 6-acetyl, benzoyl, methyl or allyl-9-carbamoyl-6,7-dihydro-5H-dibenzo[c,e]azepin-5-one.

EXAMPLE 7

9-Carboxy-6,7-dihydro-5H-dibenzo[c,e]azepin-5-one

One gram (.002 mole) of 9-carbamyl-6,7-dihydro-5H-dibenzo[c,e]azepin-5-one is warmed in 20 ml. of 75% sulfuric acid at about 75°C. To this mixture is added 800 mg. of sodium nitrite over a 20 minute period. The reaction mixture is maintained at 75°C. for 1 additional hour, cooled and poured onto ice. The crude carboxylic acid is collected and purified by extraction into dilute potassium carbonate solution. Acidification of this solution with acetic acid gives the product, 9-carboxy-6,7-dihydro-5H-dibenzo[c,e]azepin-5-one.

When 6-methyl or allyl-9-carbamoyl-6,7-dihydro-5H-dibenzo[c,e]azepin-5-one is substituted for 9-carbamoyl-6,7-dihydro-5H-dibenzo[c,e]azepin-5-one, there is obtained 6-methyl or allyl-9-carboxy-6,7-dihydro-5H-dibenzo[c,e]azepin-5-one.

EXAMPLE 8

9-(N,N-Dimethylcarbamyl)-6,7-dihydro-5H-dibenzo[c,e]azepin-5-one

One gram (.004 mole) of 9-carboxy-6,7-dihydro-5H-dibenzo[c,e]azepin-5-one is refluxed in 20 ml. of thionyl chloride for 3 hours. The excess reactant is removed in vacuo and the residue is dissolved in acetone. The resulting solution is added to a cooled and stirred solution of 20 ml. of 40% aqueous dimethylamine over a 15 minute period. The crude product, 9-(N,N-dimethylcarbamyl)-6,7-dihydro-5H-dibenzo[c,e]azepin-5-one, is filtered and recrystallized from dimethylformamide-ether.

When 6-methyl or allyl-9-carboxy-6,7-dihydro-5H-dibenzo[c,e]azepin-5-one is substituted for 9-carboxy-6,7-dihydro-5H-dibenzo[c,e]azepin-5-one, there is obtained 6-methyl or allyl-9-(N,N'-dimethylcarbamyl)-6,7-dihydro-5H-dibenzo[c,e]azepin-5-one.

EXAMPLE 9

6-Acetyl-6,7-dihydro-5H-dibenzo[c,e]azepin-5-one

To 2 g. of 6,7-dihydro-5H-dibenzo[c,e]azepin-5-one is added 20 ml. of acetic anhydride. The resulting mixture is heated on the steam-bath at 90-95°C. overnight.

The excess solvent is removed in vacuo and the residue crystallizes upon the addition of ether. The crude product, 6-acetyl-6,7-dihydro-5H-dibenzo[c,e]azepin-5-one, is recrystallized from benzene, m.p. 123-124°C.

5

When benzoic anhydride or phenylpropionyl chloride is substituted for acetic anhydride, there is obtained 6-benzoyl-6,7-dihydro-5H-dibenzo[c,e]azepin-5-one or 6-phenylpropionyl-6,7-dihydro-5H-dibenzo[c-e]azepin-5-one, respectively.

EXAMPLE 10

9-Nitro-6-acetyl-6,7-dihydro-5H-dibenzo[c,e]azepin-5-one

The procedure of Example 9 is repeated, except that the starting material is 9-nitro-6,7-dihydro-dibenzo[c,e]azepin-5-one. Using the same reaction conditions and techniques, there is obtained the product, 9-nitro-6-acetyl-6,7-dihydro-5H-dibenzo[c,e]azepin-5-one.

20

EXAMPLE 11

9-(N,N-Dimethylcarbamyl)-6-acetyl-6,7-dihydro-5H-dibenzo[c,e]azepin-5-one

The procedure of Example 9 is repeated, except that the starting material is 9-(N,N-dimethylcarbamyl)-6,7-dihydro-5H-dibenzo[c,e]azepin-5-one. Using the same reaction conditions and techniques, there is obtained the product, 9-(N,N-dimethylcarbamyl)-6-acetyl-6,7-dihydro-5H-dibenzo[c,e]azepin-5-one.

30

EXAMPLE 12

7-Succinimido-6,7-dihydro-5H-dibenzo[c,e]azepin-5-one

A mixture containing 2 g. of 6,7-dihydro-5H-dibenzo[c,e]azepin-5-one, 2.7 g. of N-bromosuccinimide and 50 mg. of benzoyl-peroxide is refluxed in 100 ml. of chloroform for 15 hours. The reaction solution is evaporated to a thick gum which is then dissolved in 30 ml. of ethanol. The careful addition of water causes the product to crystallize. The product, 7-succinimido-6,7-dihydro-5H-dibenzo[c,e]azepin-5-one, is purified by recrystallization with dimethylformamide-ether, m.p. 281-283°C.

40

When N-bromo-acetamide or N-bromo-phthalimide is substituted for N-bromosuccinimide, there is obtained 7-acetyl-6,7-dihydro-5H-dibenzo[c,e]azepin-5-one or 7-phthalimido-6,7-dihydro-5H-dibenzo[c,e]azepin-5-one, respectively.

50

EXAMPLE 13

The procedure of Example 2 is repeated, except that the starting material is 6-acetyl, benzoyl, methyl or allyl-6,7-dihydro-5H-dibenzo[c,e]azepin-5-one. Using the same reaction conditions and techniques, there is obtained the product, 6-acetyl, benzoyl, methyl or allyl-9-nitro-6,7-dihydro-5H-dibenzo[c,e]azepin-5-one.

60

EXAMPLE 14

6-Methyl-6,7-dihydro-5H-dibenzo[c,e]azepin-5-one

To a solution of 2.1 g. of 6,7-dihydro-5H-dibenzo[c,e]azepin-5-one in 50 ml. of cold dimethylformamide is added 240 mg. of sodium hydride with stirring. To this reaction mixture is added 1.5 g. of methyl iodide. The solution is allowed to stir at room temperature for several hours. The addition of water precipitates the product, 6-methyl-6,7-dihydro-5H-dibenzo[c,e]azepin-5-one. The product is purified by chromatography.

EXAMPLE 15

9-Nitro-6-methyl-6,7-dihydro-5H-dibenzo[c,e]azepin-5-one

The procedure of Example 14 is repeated, except that the starting material is 9-nitro-6,7-dihydro-5H-dibenzo[c,e]azepin-5-one. Using the same reaction conditions and techniques, there is obtained the product, 9-nitro-6-methyl-6,7-dihydro-5H-dibenzo[c,e]azepin-5-one.

EXAMPLE 16

6-Acetyl-9-acetylamino-6,7-dihydro-5H-dibenzo[c,e]azepin-5-one

1.1 Grams (.005 mole) of 9-amino-6,7-dihydro-5H-dibenzo[c,e]azepin-5-one is heated in 20 ml. of acetic anhydride on the steam-bath at 90-95°C. for 18 hours. Most of the excess anhydride is removed in vacuo and the residue is triturated with water until solidification. The product, 6-acetyl-9-acetylamino-6,7-dihydro-5H-dibenzo[c,e]azepin-5-one, is purified by crystallization from benzene.

When benzoic anhydride or propionic anhydride is substituted for acetic anhydride, there is obtained 6-benzoyl-9-benzoylamino-6,7-dihydro-5H-dibenzo[c,e]azepin-5-one or 6-propionyl-9-propionylamino-6,7-dihydro-5H-dibenzo[c,e]azepin-5-one, respectively.

EXAMPLE 17

9-Methylthio-6,7-dihydro-5H-dibenzo[c,e]azepin-5-one

A mixture containing 380 mg. of copper powder, 10 ml. of 2,4-lutidine and 660 mg. of dimethyl disulfide is heated at 125°C. for 4 hours. The mixture is cooled and 1.5 g. of 9-bromo-6,7-dihydro-5H-dibenzo[c,e]azepin-5-one is added. This mixture is heated at 155°C. for 18 hours. The solvent is evaporated and the product, 9-methylthio-6,7-dihydro-5H-dibenzo[c,e]azepin-5-one, is isolated from the residue by column chromatography.

When diphenyl disulfide or dibenzyl disulfide is substituted for dimethyl disulfide, there is obtained 9-phenylthio-6,7-dihydro-5H-dibenzo[c,e]azepin-5-one or 9-benzylthio-6,7-dihydro-5H-dibenzo[c,e]azepin-5-one, respectively.

EXAMPLE 18

9-Methylsulfinyl-6,7-dihydro-5H-dibenzo[c,e]azepin-5-one

To a cooled solution of 2.4 g. of 9-methylthio-6,7-dihydro-5H-dibenzo[c,e]azepin-5-one in 50 ml. of acetone and 50 ml. of methanol is added a solution of 2.1 g. of sodium periodate in 30 ml. of water over one hour. The reaction mixture is stirred overnight. Most of the organic solvent is evaporated and the crude product, 9-methylsulfinyl-6,7-dihydro-5H-dibenzo[c,e]azepin-5-one, can be recrystallized or purified by column chromatography.

When 9-phenylthio-6,7-dihydro-5H-dibenzo[c,e]azepin-5-one or 9-benzylthio-6,7-dihydro-5H-dibenzo[c,e]azepin-5-one is substituted for 9-methylthio-6,7-dihydro-5H-dibenzo[c,e]azepin-5-one, there is obtained 9-phenylsulfinyl-6,7-dihydro-5H-dibenzo[c,e]azepin-5-one or 9-benzylsulfinyl-6,7-dihydro-5H-dibenzo[c,e]azepin-5-one, respectively.

EXAMPLE 19

9-Methylsulfonyl-6,7-dihydro-5H-dibenzo[c,e]azepin-5-one

To a solution containing 2.5 g. of 9-methylsulfinyl-6,7-dihydro-5H-dibenzo[c,e]azepin-5-one and 50 ml. of acetic acid at about 20°C. is added, with stirring, an excess of 30% hydrogen peroxide in acetic acid, drop-wise, over 30 minutes. The reaction mixture is maintained at room temperature with slight agitation for 16 hours, then poured into ice and filtered to obtain the product, 9-methylsulfonyl-6,7-dihydro-5H-dibenzo[c,e]azepin-5-one.

10 When 9-phenylsulfinyl-6,7-dihydro-5H-dibenzo[c,e]azepin-5-one or 9-benzylsulfinyl-6,7-dihydro-5H-dibenzo[c,e]azepin-5-one is substituted for 9-methylsulfinyl-6,7-dihydro-5H-dibenzo[c,e]azepin-5-one, there is obtained 9-phenylsulfonyl-6,7-dihydro-5H-dibenzo[c,e]azepin-5-one or 9-benzylsulfonyl-6,7-dihydro-5H-dibenzo[c,e]azepin-5-one, respectively.

EXAMPLE 20

9-Mercapto-6,7-dihydro-5H-dibenzo[c,e]azepin-5-one

20 A mixture of 1.2 g. of 9-methylthio-6,7-dihydro-5H-dibenzo[c,e]azepin-5-one and 5 g. (.04 mole) of pyridine hydrochloride under a nitrogen atmosphere is placed in an oil-bath at 230°C. The mixture is heated for 10 minutes, cooled and extracted with hot ethyl acetate. The ethyl acetate extracts are evaporated to obtain the product, 9-mercaptop-6,7-dihydro-5H-dibenzo[c,e]azepin-5-one.

EXAMPLE 21

9-Trifluoromethyl-6,7-dihydro-5H-dibenzo[c,e]azepin-5-one

35 A mixture containing 2.5 g. of 9-carboxy-6,7-dihydro-5H-dibenzo[c,e]azepin-5-one, hydrogen fluoride, and about 0.05 mole of sulfur tetrafluoride in a stainless steel lined shaker is heated at 120°C. for 8 hours. The reaction mixture is cooled, vented, and then concentrated. The crude product, 9-trifluoromethyl-6,7-dihydro-5H-dibenzo[c,e]azepin-5-one, can be purified by crystallization or column chromatography.

EXAMPLE 22

9-Trifluoromethyl-6-acetyl-6,7-dihydro-5H-dibenzo[c,e]azepin-5-one

45 The procedure of Example 9 is repeated, except that the starting material is 9-trifluoromethyl-6,7-dihydro-5H-dibenzo[c,e]azepin-5-one. Using the same reaction conditions and techniques, there is obtained the product, 9-trifluoromethyl-6-acetyl-6,7-dihydro-5H-dibenzo[c,e]azepin-5-one.

EXAMPLE 23

9-Bromo-6,7-dihydro-5H-dibenzo[c,e]azepin-5-one

55 To a stirred solution of 2.2 g. of 9-amino-6,7-dihydro-5H-dibenzo[c,e]azepin-5-one, 25 ml. of concentrated sulfuric acid and 25 ml. of water at 0°C. is added a solution which contains 1 g. of sodium nitrite in 10 ml. of water over 15 minutes. The reaction is stirred for another 30 minutes at 0°C., then added in portions of a solution of 5 g. of cuprous bromide in 15 ml. of 48% hydrogen bromide which is heated on the steam-bath at ca. 60°C. for 20 minutes. The reaction mixture is filtered and the crude product, 9-bromo-6,7-dihydro-5H-dibenzo[c,e]azepin-5-one, is purified by elution on alumina with ethyl acetate. The m.p. of pure material is 228-230°C.

When cuprous chloride or cuprous iodide is substituted for cuprous bromide, and the corresponding halo

acid is used, there is obtained 9-chloro-6,7-dihydro-5H-dibenzo[c,e]azepin-5-one or 9-iodo-6,7-dihydro-5H-dibenzo[c,e]azepin-5-one, respectively.

EXAMPLE 24

9-Methoxy-6,7-dihydro-5H-dibenzo[c,e]azepin-5-one

2.2 Grams of 9-hydroxy-6,7-dihydro-5H-dibenzo[c,e]azepin-5-one is dissolved in 30 ml. of dry dimethylformamide. The solution is cooled in ice and 810 mg. of sodium methoxide is added. The mixture is stirred at room temperature for 15 minutes, then cooled in ice and 2.1 g. of methyl iodide is added over 10 minutes. The reaction mixture is stirred in ice an additional 5 minutes and then at room temperature for an hour. The reaction is warmed on the steam-bath for 10 minutes, filtered and the filtrate is diluted with 0.5 N sodium hydroxide solution until the product crystallizes. The product, 9-methoxy-6,7-dihydro-5H-dibenzo[c,e]azepin-5-one, is purified from benzene-petroleum ether, m.p. 183°C.

When benzyl chloride is substituted for methyl iodide, there is obtained 9-benzyloxy-6,7-dihydro-5H-dibenzo[c,e]azepin-5-one.

EXAMPLE 25

9-Hydroxy-6,7-dihydro-5H-dibenzo[c,e]azepin-5-one

1.1 Grams of 9-amino-6,7-dihydro-5H-dibenzo[c,e]azepin-5-one is dissolved in 40 ml. of 6 N sulfuric acid. The solution is cooled in ice while adding, with agitation, 380 mg. (0.006 mole) of sodium nitrite in 5 ml. of water over 10 minutes. The reaction mixture is maintained in ice for 30 minutes and allowed to reach room temperature over 1 hour. The solution is warmed on the steam-bath for 25 minutes and the crude product is filtered. The crude product, 9-hydroxy-6,7-dihydro-5H-dibenzo[c,e]azepin-5-one, is purified by dissolving in 2.5 N sodium hydroxide and precipitated by neutralizing with acetic acid, m.p. 290°C., dec.

EXAMPLE 26

3,9-Dinitro-6,7-dihydro-5H-dibenzo[c,e]azepin-5-one

To a solution containing 2.1 g. (0.01 mole) of 6,7-dihydro-5H-dibenzo[c,e]azepin-5-one and 30 ml. of concentrated sulfuric acid cooled in ice is added 2.2 g. (0.022 mole) of potassium nitrate in 20 ml. of concentrated sulfuric acid over 30 minutes. The reaction mixture is allowed to stand at room temperature overnight, poured onto ice and filtered to obtain the crude dinitro product. Recrystallization from dimethylformamide-ethanol gives the product, 3,9-dinitro-6,7-dihydro-5H-dibenzo[c,e]azepin-5-one, m.p. 328°C., dec.

When 6-acetyl, benzoyl, methyl or allyl-6,7-dihydro-5H-dibenzo[c,e]azepin-5-one is substituted for 6,7-dihydro-5H-dibenzo[c,e]azepin-5-one, there is obtained 6-acetyl, benzoyl, methyl or allyl-3,9-dinitro-6,7-dihydro-5H-dibenzo[c,e]azepin-5-one.

EXAMPLE 27

9-Amidino-6,7-dihydro-5H-dibenzo[c,e]azepin-5-one

Into a cold suspension of equal molar quantities of 9-cyano-6,7-dihydro-5H-dibenzo[c,e]azepin-5-one and ethanol is passed dry hydrogen chloride until the mixture is saturated. After standing 24 hours, the excess hydrogen chloride is removed and an excess of aqueous ammonia added. The resulting compound is 9-amidino-6,7-dihydro-5H-dibenzo[c,e]azepin-5-one.

EXAMPLE 28

9-Ureido-6,7-dihydro-5H-dibenzo[c,e]azepin-5-one

9-Amino-6,7-dihydro-5H-dibenzo[c,e]azepin-5-one is dissolved in acetic acid and treated with a slight excess of potassium isocyanate. The resulting product is 9-ureido-6,7-dihydro-5H-dibenzo[c,e]azepin-5-one.

EXAMPLE 29

10 9-(Ethylcarbamyl)oxy-6-methyl-6,7-dihydro-5H-dibenzo[c,e]azepin-5-one

To a mixture of 9-hydroxy-6-methyl-6,7-dihydro-5H-dibenzo[c,e]azepin-5-one in dioxane is added ethyl isocyanate to yield the title compound.

EXAMPLE 30

9-Sulfamyl-6-methyl-6,7-dihydro-5H-dibenzo[c,e]azepin-5-one

6-Methyl-6,7-dihydro-5H-dibenzo[c,e]azepin-5-one is added with stirring to a cold excess of chlorosulfonic acid. After the addition is complete, the solution is slowly allowed to rise to room temperature. After 2 hours, the solution is cautiously added to cold concentrated ammonium hydroxide. The title compound precipitates.

EXAMPLE 31

9-(1,1,2-Trifluoro-2-chloroethoxy)-6,7-dihydro-5H-dibenzo[c,e]azepin-5-one

30 Into a solution of 5 grams of 9-hydroxy-6,7-dihydro-5H-dibenzo[c,e]azepin-5-one in 150 ml. of dimethylformamide is added 500 mg. of sodium methoxide and an excess of trifluorochloro ethylene. This solution is heated in a bomb at 100°C. for 6 hours. The addition of water precipitates the product.

EXAMPLE 32

6-Carbethoxy-6,7-dihydro-5H-dibenzo[c,e]azepin-5-one

40 To a cold solution of 6,7-dihydro-5H-dibenzo[c,e]azepin-5-one in dimethylformamide is added one equivalent of sodium hydride, which is then stirred until a solution is obtained. To this is added one equivalent of ethyl chlorocarbonate and the mixture stirred for 2 hours. Addition of water precipitates the title compound.

EXAMPLE 33

50 9-Carbamyl-6,7-dihydro-5H-dibenzo[c,e]azepin-5-one

The above compound (9-carbethoxy-6,7-dihydro-5H-dibenzo[c,e]azepin-5-one) is warmed in ammonium hydroxide for one hour to give the title compound.

EXAMPLE 34

6-(Methylthiomethyl)-6,7-dihydro-5H-dibenzo[c,e]azepin-5-one

60 A cold solution of 6,7-dihydro-5H-dibenzo[c,e]azepin-5-one in dimethylformamide is treated with one equivalent of sodium hydride. After the reaction is over, an equivalent of chloromethyl methylsulfide is added. The reaction mixture is stirred for 2 hours, and then water is added to precipitate the product.

EXAMPLE 35

6-Methylsulfinylmethyl-6,7-dihydro-5H-dibenzo[c,e]azepin-5-one

6-Methylthiomethyl-6,7-dihydro-5H-dibenzo[c,e]azepin-5-one in acetone solution is oxidized with sodium periodate to give the corresponding sulfoxide.

EXAMPLE 36

6-Acetyl-9-acetylamino-10-nitro-6,7-dihydro-5H-dibenzo[c,e]azepin-5-one

1.5 Grams (0.005 mole) of 6-acetyl-9-acetylamino-6,7-dihydro-5H-dibenzo[c,e]azepin-5-one in 5 ml. of sulfuric acid is treated with 20 ml. of concentrated sulfuric acid which contains 0.5 g. (0.005 mole) of potassium nitrate. The resulting mixture is maintained with stirring at 0°C. to 10°C. for 6 hours and then poured onto ice to precipitate the product.

EXAMPLE 37

9-Methoxy-10-nitro-6,7-dihydro-5H-dibenzo[c,e]azepin-5-one

A solution of 2.4 g. (0.01 mole) of 9-methoxy-6,7-dihydro-5H-dibenzo[c,e]azepin-5-one in 30 ml. of concentrated sulfuric acid is titrated with a solution containing 1 g. (0.01 mole) of potassium nitrate in 10 ml. of concentrated sulfuric acid at ice temperature. After 5 hours at ice temperature, the solution is poured onto ice and the product precipitates.

Other representative compounds in addition to those previously indicated which may be prepared according to the above processes include:

- 9-dimethylamino-6,7-dihydro-5H-dibenzo[c,e]azepin-5-one
- 6-methyl-9-dimethylamino-6,7-dihydro-5H-dibenzo[c,e]azepin-5-one
- 3,9-dimethylthio-6-aminomethyl-6,7-dihydro-5H-dibenzo[c,e]azepin-5-one
- 6-carboxymethyl-9-methylamino-6,7-dihydro-5H-dibenzo[c,e]azepin-5-one
- 6-vinyl-9-nitro-6,7-dihydro-5H-dibenzo[c,e]azepin-5-one
- 7-phthalimido-6,7-dihydro-5H-dibenzo[c,e]azepin-5-one
- 7-acetylido-6-methoxymethyl-6,7-dihydro-5H-dibenzo[c,e]azepin-5-one
- 9-methylsulfinyl-6,7-dihydro-5H-dibenzo[c,e]azepin-5-one
- 9-methylsulfonyl-6,7-dihydro-5H-dibenzo[c,e]azepin-5-one
- 9-dimethylcarbamoyl-6,7-dihydro-5H-dibenzo[c,e]azepin-5-one
- 9-phenoxy-6,7-dihydro-5H-dibenzo[c,e]azepin-5-one
- 9-phenethoxy-6,7-dihydro-5H-dibenzo[c,e]azepin-5-one
- 9-carboxymethyl-6,7-dihydro-5H-dibenzo[c,e]azepin-5-one
- 9- α -(carboxy)ethyl-6,7-dihydro-5H-dibenzo[c,e]azepin-5-one
- 9- α -(carboxy)ethenyl-6,7-dihydro-5H-dibenzo[c,e]azepin-5-one
- 9- α -(carboxy)propyl-6,7-dihydro-5H-dibenzo[c,e]azepin-5-one
- 3,9-dipropenylcarbamoyl-6,7-dihydro-5H-dibenzo[c,e]azepin-5-one
- 9-benzylsulfonyl-6,7-dihydro-5H-dibenzo[c,e]azepin-5-one
- 9-phenylsulfinyl-6,7-dihydro-5H-dibenzo[c,e]azepin-5-one
- 9-benzylthio-6,7-dihydro-5H-dibenzo[c,e]azepin-5-one

9-p-chlorobenzoyl-6-acetyl-6,7-dihydro-5H-dibenzo[c,e]azepin-5-one
9-allylsulfinyl-6,7-dihydro-5H-dibenzo[c,e]azepin-5-one

- 5 3,9-dinitro-7-succinimido-6,7-dihydro-5H-dibenzo[c,e]azepin-5-one
- 10 3,9-diamino-6-methoxymethyl-6,7-dihydro-5H-dibenzo[c,e]azepin-5-one
9-acetylamino-6-carboxymethyl-6,7-dihydro-5H-dibenzo[c,e]azepin-5-one
- 15 3,9-dihydroxy-6-acetyl-6,7-dihydro-5H-dibenzo[c,e]azepin-5-one
9-mercaptop-6-ethyl-6,7-dihydro-5H-dibenzo[c,e]azepin-5-one
- 20 3,9-bis-methylethylamino-6,7-dihydro-5H-dibenzo[c,e]azepin-5-one
9-anilino-6,7-dihydro-5H-dibenzo[c,e]azepin-5-one
- 25 3,9-diacylaminio-6-acetyl-6,7-dihydro-5H-dibenzo[c,e]azepin-5-one
9-p-tolylthio-6,7-dihydro-5H-dibenzo[c,e]azepin-5-one
- 30 9-phenylsulfonyl 6-vinyl-6,7-dihydro-5H-dibenzo[c,e]azepin-5-one
3,9-diphenylsulfonyl-6-vinyl-6,7-dihydro-5H-dibenzo[c,e]azepin-5-one
- 35 9-cyano-6-methyl-6,7-dihydro-5H-dibenzo[c,e]azepin-5-one
3,9-dibromo-6-carboxymethyl-6,7-dihydro-5H-dibenzo[c,e]azepin-5-one
- 40 3,9-dicyano-6,7-dihydro-5H-dibenzo[c,e]azepin-5-one
9-carboxy-6-hydroxymethyl-6,7-dihydro-5H-dibenzo[c,e]azepin-5-one
- 45 3,9-dicarbamoyl-6-propenyl-6,7-dihydro-5H-dibenzo[c,e]azepin-5-one
9-nitro-6-ethyl-7-acetylido-6,7-dihydro-5H-dibenzo[c,e]azepin-5-one
- 50 3,9-dimethylthio-6-benzoyl-6,7-dihydro-5H-dibenzo[c,e]azepin-5-one
3,9-diphenylsulfinyl-6-benzoyl-6,7-dihydro-5H-dibenzo[c,e]azepin-5-one
- 55 9-fluoro-6-acetyl-6,7-dihydro-5H-dibenzo[c,e]azepin-5-one
45 9-(p-methylthiobenzylamino)-6,7-dihydro-5H-dibenzo[c,e]azepin-5-one

What is claimed is:

1. A compound of the formula:

wherein

- 60 R₁ is hydrogen
- R₂ is hydrogen or nitro;
- R₃ is hydrogen, alkyl of up to three carbon atoms, alkanoyl of up to four carbon atoms, benzoyl, carboalkoxy of up to four carbon atoms, alkenyl of up to four carbon atoms, alkylthioalkyl of up to four carbon atoms, or methylsulfinylmethyl;
- R₄ is hydrogen, succinimido, acetylido or phthalimido;
- R₉ is hydrogen, nitro, amino, halo, alkoxy of up to

four carbon atoms, hydroxy, cyano, carbamyl, carboxy, dialkylcarbamyl of up to four carbon atoms, alkanoylamino of up to four carbon atoms, benzoylamino, alkylthio of up to four carbon atoms, phenylthio, benzylthio, alkylsulfinyl of up to three carbon atoms, alkylsulfonyl of up to three carbon atoms, phenylsulfinyl, benzylsulfinyl, mercapto, trifluoromethyl, amidino, ureido, alkylcarbamylloxy of up to four carbon atoms or sulfamyl; and R₁₀ is hydrogen;

with the proviso that when R₃ is hydrogen or methyl at least one of R₂, R₄ or R₉ is other than hydrogen.

2. A compound of the formula:

R₁ is hydrogen;

R₂ is hydrogen or nitro;

R₃ is hydrogen, methyl, acetyl, benzoyl, propionyl, carbethoxy, methylthiomethyl, or methylsulfinylmethyl;

R₄ is hydrogen, succinimido, acethylimido, or phthalimido;

R₉ is hydrogen, nitro, amino, fluro, bromo, chloro, dimethylcarbamyl, acetylarnino, benzoylamino, allyl propionylarnino, methylthio, phenylthio, benzylthio, methylsulfinyl, methylsulfonyl, phenylsulfinyl, benzylsulfinyl, mercapto, trifluoromethyl, amidino, ureido, ethylcarbamylloxy, or sulfamyl; and

R₁₀ is hydrogen;

with the proviso that when R₃ is hydrogen, or methyl at least one of R₂, R₄ or R₉ is other than hydrogen.

3. A compound of the formula:

wherein

R₁, R₂, R₄ and R₁₀ are each hydrogen;

R₃ is alkanoyl of up to four carbon atoms; and

R₉ is hydrogen, nitro, amino, halo, alkoxy of up to four carbon atoms, hydroxy, cyano, carbamyl, carboxy, dialkylcarbamyl of up to four carbon atoms, alkanoylamino of up to four carbon atoms, benzoylamino, alkylthio of up to four carbon atoms, phenylthio, benzylthio, alkylsulfinyl of up to three carbon atoms, alkylsulfonyl of up to three carbon atoms, phenylsulfinyl, benzylsulfinyl, mercapto, trifluoromethyl, amidino, ureido, alkylcarbamylloxy of up to four carbon atoms or sulfamyl.

4. A compound of claim 3 wherein

R₃ is acetyl.

5. A compound of claim 3 wherein

R₃ is butyryl.

6. A compound of claim 3 wherein

R₉ is hydrogen

R₃ is acetyl.

7. A compound of claim 3 wherein

R₉ is hydrogen, and

R₃ is butyryl.

8. A compound of the formula:

wherein

R₁, R₂, R₄ and R₁₀ are each hydrogen,

R₃ is alkenyl of up to four carbon atoms, and

R₉ is hydrogen, nitro, amino, halo, alkoxy of up to four carbon atoms, hydroxy, cyano, carbamyl, carboxy, dialkylcarbamyl of up to four carbon atoms, alkanoylamino of up to four carbon atoms, phenylthio, benzylthio, alkylsulfinyl of up to three carbon atoms, alkylsulfonyl of up to three carbon atoms, phenylsulfinyl, benzylsulfinyl, mercapto, trifluoromethyl, amidino, ureido, alkylcarbamylloxy of up to four carbon atoms or sulfamyl.

9. A compound of claim 8 wherein R₃ is allyl.

10. A compound of the formula:

wherein

R₂, R₃, R₄ and R₁₀ are each hydrogen,

R₁ is amino, and

R₉ is hydrogen, nitro, amino, halo, alkoxy of up to four carbon atoms, hydroxy, cyano, carbamyl, carboxy, dialkylcarbamyl of up to four carbon atoms, alkanoylamino of up to four carbon atoms, phenylthio, benzylthio, alkylsulfinyl of up to three carbon atoms, alkylsulfonyl of up to three carbon atoms, phenylsulfinyl, benzylsulfinyl, mercapto, trifluoromethyl, amidino, ureido, alkylcarbamylloxy of up to four carbon atoms or sulfamyl.

11. A compound of the formula:

65 wherein

R₂, R₃, R₄ and R₁₀ are each hydrogen,

R₁ is halogen, and

R₉ is hydrogen, nitro, amino, halo, alkoxy of up to

four carbon atoms, hydroxy, cyano, carbamyl, carboxy, dialkylcarbamyl of up to 4 carbon atoms, alkanoylamino of up to four carbon atoms, phenylthio, benzylthio, alkylsulfinyl of up to three carbon atoms, alkylsulfonyl mercapto, trifluoromethyl, amidino, ureido, alkylcarbamyl of up to four carbon atoms or sulfamyl.

12. A compound of claim 11 wherein R₁ is fluoro and R₉ is hydrogen.
 13. A compound of claim 11 wherein R₁ is chloro and R₉ is hydrogen.
